UNITED STATES PATENT OFFICE.

CHARLES H. THURSTON, OF MARLBOROUGH, NEW HAMPSHIRE, ASSIGNOR
TO THURSTON MANUFACTURING COMPANY.

SEWING-MACHINE.

SPECIFICATION forming part of Letters Patent No. 240,201, dated April 12, 1881.

Application filed September 13, 1880. (No model.)

To all whom it may concern:

Be it known that I, CHARLES H. THURSTON, of Marlborough, county of Cheshire, State of New Hampshire, have invented an improvement in Sewing-Machines, of which the following description, in connection with the accompanying drawings, is a specification.

This invention in sewing-machines relates, chiefly, to improvements in mechanism for imparting a variable motion to the shuttle.

In my improved machine the under thread is supplied from a shuttle held in a vibrating carrier connected with a horizontal rocker-shaft extended from end to end of the machine under the cloth-plate, such devices being common. To this rocker-shaft I have added an arm, made as an open loop, and denominated by me as the "looped arm." The elongated opening of this looped arm receives a stud provided with a loose block, the stud being connected with the lower end of a link actuated by a crank on the upper rotating or needle-bar-operating shaft, the said link being joined with a radius-bar, so that the said link, as it is raised and lowered by the crank, is moved laterally, to thereby cause the said stud and block at the lower end of the link to approach toward and recede from the axis of the said rocker-shaft, it moving the said rocker-shaft the fastest as it approaches its center in traveling within the looped arm, and vice versa. The feeding-bar, moved forward positively by an arm of a rocker-shaft, rests upon a lifting-bar, which is raised positively by a roll on an arm of the shuttle-operating rock-shaft, the said roll elevating the lifting-bar and raising the toothed surface of the feeding-bar against the fabric or material being sewed, when it is to be engaged and fed forward. A suitable spring retracts and lowers the feeding-bar at the proper time.

Figure 1 represents an under-side view of a sewing-machine containing my improvements; Fig. 2, a front view of the machine, the bearing for the front end of the under rocker-shaft being broken away to show the feeding devices; Fig. 3, a vertical section, taken at the rear of the machine, to illustrate clearly the upper rotating main shaft and the intermediate connections between it and the shuttle and feed-

actuating rocker-shafts; Figs. 4, 5, 6, details of the shuttle-carrier, and spring-finger to retain the shuttle in place in the carrier, or permit it to be easily removed; Fig. 7, a detail of the looped arm; and Fig. 8 a detail of the feed-bar.

The cloth-plate A and the head B and frame C, constituting part of the usual standard and overhanging arm, are and may be of usual construction, as may be the needle-bar D, 60 needle *p*, and presser-bar E and its foot.

The main or driven shaft *a*, located in the usual overhanging arm, and rotated positively to actuate the needle-bar by a heart-cam, or otherwise, not of my invention, has upon it a 65 crank *b*, and an eccentric, *c*. (See Fig. 3.) The crank *b* is embraced by an ordinary two-part collar at the upper end of the link *F*, the latter having at its lower end a stud, *d*. The block and stud enter within the elongated slot 70 *e* of the looped arm *G*, connected with the shuttle-carrier-operating rocker-shaft *G*² by a screw, *e*². This looped arm will preferably be composed of a piece of metal bent or forged into the form shown in Fig. 7, and screwed to 75 the said shaft. The link *F*, between its ends, is loosely connected at *e*² with one end of a radius-bar, *H*, pivoted at *e*³ upon a lug at the under side of the cloth-plate. This rocker-shaft *G*², near its front end, has secured upon 80 it the shuttle-carrying arm *I*, having at its upper end a surface, *2*, upon which the shuttle rests as it is carried forward through the loop of needle-thread by the horns of the carrier in the usual manner.

Rotation of the crank *b* actuates the link *f* and causes its lower end to rise and fall, and the radius-bar, during such time, causes the crank-pin to be moved out away from and in toward the center of the said rocker-shaft *G*². 90 As the crank reaches its lowest position the shuttle reaches its backward position and almost stops, while the crank moves a little and turns the link *F* on the pivot *e*², causing the block and stud to move toward the shaft *G*², 95 along within the looped arm *G*, into the position shown in Fig. 3. Further rotation of the crank lifts the link *F*, and as the block and stud are then held nearest the center of the shaft *G*² the shuttle-carrier will be moved to 100

cause the shuttle (not shown) to quickly enter and pass through the loop of needle-thread. Just as the heel of the shuttle passes through the loop of needle-thread the block and stud 5 commence to travel outward along the space in the looped arm, and the shuttle and shuttle-carrier remain at rest, while the needle clears the upper side of the fabric being sewed, and the feed takes place. The block and stud reach the 10 outer end of the space in the said looped arm a little before the needle reaches its highest position. The block and stud, in their descent, commence to act within the looped arm next its outer end and start the shuttle-carrier backward slowly while the needle completes its 15 upward motion, and as the crank *b* descends from near its highest to its lowest point the block and stud again gradually approach the center of the shaft *G*², and the needle-bar and 20 needle descend quickly, the needle reaching its lowest position just as the shuttle reaches its most backward position, and then the needle-bar rises slowly, while the shuttle is again moved forward rapidly, as before described.

25 The shuttle-carrier has a spring-finger, *f*, connected with a rod, *f'*, to retain the finger in the position shown in Fig. 4. Instead of lifting this finger positively, I add to the carrier a cam-ledge, 3, that acts to raise and hold 30 the spring *f* as the latter is pushed aside from over the shuttle in the carrier.

The feeding-bar *g* (shown separately in Fig. 8) has a slot, *g'*, in which is entered the pin or screw *g'*, upon which the feeding-bar slides, 35 and by which it is supported at its rear end. This feeding-bar, near its forward end, has a smooth straight foot, 13, that rests upon the smooth straight crown or head 4 (see Fig. 2) of the feed-lifting lever *h*, having its fulcrum 40 on the stud *g'*, before described, upon which the feeding-bar slides, and about which it also turns or vibrates as it is raised and lowered. The feed-bar has its slot packed at one end with leather, as at 5, to lessen noise when the 45 feed-bar strikes the pin *g'*, and the said bar is also provided with a second piece of leather at 6, to strike against the feed-regulating stop 4, which latter is shown as a sliding wedge attached to a rod, *i'*, screw-threaded at 7, and 50 provided with a milled nut, *i*³, the periphery of which is extended through a slot, 8, in the cloth-plate *A*, as seen in Fig. 3. This nut may be operated by the thumb or finger, and as the nut is held against longitudinal movement

it follows that the rod and wedge will be moved 55 backward or forward, according to the direction in which the nut is turned. The length of stitch may be readily controlled by this operation.

The feed-lifting lever is curved or recessed 60 at its lower side, and bears upon a roller-stud, *j*, of an arm, *j'*, of the rocker-shaft *G*², and as the said shaft is rotated the roller-stud acts to lift or elevate the lifting-lever to raise the feeding-bar, so that its teeth will engage the 65 fabric and retain the said bar lifted while it is being moved forward the length of the stitch, when the lifting-bar is permitted to fall, and with it the feeding-bar, which is quickly thrown down and back by the spring *i'*. 70

The feeding-bar is moved forward positively by the arm *k* at the front end of the feed-operating rock-shaft *k*², the said arm being provided at its upper end with a stud or roller, as shown in Fig. 2, located within a notch at 75 the upper end of the feeding-bar. This rock-shaft *k*² has an arm, 10, with which is pivoted the lower end of a link, *m*, that at its upper end is made to embrace the eccentric *e* on the main driven shaft of the machine. 80

The take-up is of usual construction and operation.

The shafts *G*² *k*² are sustained upon pointed screws.

Instead of crank *b*, I might employ an eccentric. 85

I claim—

1. In a sewing-machine, the main rotating shaft *a*, its crank, the link, its stud, and the radius-bar, combined with the shuttle-carrier-operating rock-shaft, its looped arm, and the shuttle-carrier, the said stud, when operating the said shuttle-carrier, moving away from and in toward the said shaft, substantially as and for the purpose described. 90

2. The shuttle-carrier provided with a cam-ledge, 3, combined with the shuttle-holding spring-finger *f*, adapted to be raised by the said cam as the finger is turned aside from above the shuttle in the carrier, substantially as described. 95

In testimony whereof I have signed my name to this specification in the presence of two subscribing witnesses.

CHARLES H. THURSTON.
